UNITED STATES PATENT OFFICE.

WILLIAM L. BAKER, OF NEW ORLEANS, LOUISIANA.

OIL BURNER.

Application filed February 18, 1924. Serial No. 693,614.

To all whom it may concern:

Be it known that I, WILLIAM L. BAKER, a citizen of the United States, residing at New Orleans, in the parish of Orleans and 5 State of Louisiana, have invented certain new and useful Improvements in Oil Burners; and I do declare the following to be a full, clear, and exact description of the invention, such as will enable others skilled 10 in the art to which it appertains to make and use the same.

My invention relates to improvements in oil atomizers and burners and the present disclosure is directed to a burner which mechanically atomizes the oil under high pressure and mixes the atomized oil with low pressure air.

One object of the invention is to provide 20 an exceptionally simple and inexpensive, yet an efficient means for atomizing the oil and controlling the rate of discharge thereof. In this connection, a further object is to provide a spinner actuated by the oil sprayed from the burner and so positioned as to form what 25 is commonly known a "back shot flame", that is the spinner widens the flame if necessary for certain types of fire boxes.

In the construction herein disclosed, the 30 burner body is removably carried by a supporting neck which feeds low pressure air thereto and is formed with an oil port detachably coupled to the burner, and a further object of the invention is to associate a novel form of drip pan with a coupling 35 by means of which the neck is attached to an air supply pipe, said pan being adapted to receive all drippings when the burner is disconnected from the neck, for instance, when withdrawing said burner from a heated 40 fire box after a shut down.

Yet another object is to associate an air 45 controlling valve in a novel manner with the above-named drip pan and coupling, the arrangement being such that the bottom of said pan and said coupling constitute guiding means for the valve.

With the foregoing in view, the invention 50 resides in the novel subject matter herein-after described and claimed, the description being supplemented by the accompanying drawings.

Figure 1 is a side elevation of a burner constructed in accordance with my invention.

Figure 2 is a central vertical longitudinal 55 section view.

Figure 3 is a vertical transverse section as indicated by line 3—3 of Fig. 1.

Figure 4 is an enlarged vertical sectional 60 view through the atomizing portion of the burner.

Figures 5 and 6 are transverse sectional 65 views as indicated by lines 5—5 and 6—6 of Fig. 4.

Figure 7 is an elevation showing the front 70 end of the oil controlling stem and the valve carried by the front end thereof.

In the drawings above briefly described, the numeral 1 designates a cylindrical head carried by the upper end of a tubular, air supply neck 2, the lower end of this neck 70 being preferably threaded as indicated at 3, in a central opening 4 formed in the bottom 5 of a drip pan 6. Contacting with the lower side of the bottom 5, I have illustrated a coupling collar 7 which is by preference 75 provided with lateral ears 8 through which cap screws or the like 9 pass to secure said ears to said bottom. A low pressure air supply pipe 10 is shown threaded into the coupling 7. In order to control the amount of 80 air passing from the pipe 10 through the neck 2 and into the burner, yet to be described, I provide a slidable valve plate 11 which is received in a relatively wide and shallow channel-way 12 formed in the upper 85 side of the collar 7, said plate being formed with an opening 13 to register any desired amount with the pipe 10 and the neck 2.

In the preferred form of construction, the neck 2 is provided at its juncture with the head 1, with a boss 14 in which an oil port 15 is provided, said port communicating with a high pressure oil supply pipe 16. The boss is, by preference provided with a rearwardly extending nipple 17 for reception in a packed 90 socket 18 in a downward extension 19 formed on a second cylindrical head 20 which is removably received in the head 1. The rear end of this head 20 in the construction shown, is formed with a central forwardly extending boss 21 into which an oil pipe 22 is threaded, said pipe being in communication 100 with the port 15 through the medium of a duct 23, formed in the downward extension 19. This extension is held in engagement 105 with the nipple 17 by any suitable clamping

device 24, which may be released at will, so as to allow the head 20 and parts carried thereby, to be bodily withdrawn from the head 1. Attention may here be directed to 5 the fact that a portion of the drip pan 6 extends under the nipple 17 so that whenever the clamping device 24 is released and the projection 19 disengaged from said nipple, all oil draining from the oil passages, will 10 be caught in the oil pan from which it may be drained through a suitable cock 24.

I have shown the rear end of the head 20, provided with a boss 25 in which a valve stem 26 is threaded, the rear end of said boss 15 preferably having a suitable stuffing box 27. Upon the front end of the stem 26, I provide a narrow, frusto-conical valve 28 which co-operates with a narrow frusto-conical valve seat 28' formed in the tip 29 of the oil 20 pipe 22, said tip being preferably threaded on the pipe as shown. To at all times center the valve 28 with respect to the tip 29, I provide the stem 26 with suitable webs 30.

A suitable hand wheel or the like 31, is 25 provided on the rear end of the stem 26, and by turning this wheel, it will be seen that the stem will be adjusted to space the narrow valve 28 any desired distance from the narrow seat 28'. Thus, oil under high pressure 30 may be discharged through the annular space between said valve and seat, at a high velocity, and will be sprayed from the tip, in the form of a hollow cone, having the well known advantages. I make provision for 35 supplying low pressure air to this sprayed oil, including a sleeve 32 which surrounds and is widely spaced from the tip 29 and the valve 28, the front end of said sleeve being disposed in rear of the zone of spray, so as to 40 retard the sprayed fuel, in no manner whatsoever. I have shown the sleeve 32 connected by another sleeve 33 with the front end of the hollow head 20, and this head is formed with an opening 34 by means of which it is 45 placed in communication with the neck 2, to receive low pressure air therefrom.

In certain types of furnaces, the cone sprayed from the space between the valve 28 and seat 28', may be used without any 50 means for widening the zone of spray. For instance, this arrangement may be employed to advantage in the fire boxes of Scotch boilers. In other types of fire boxes, however, it is necessary to produce a "back shot 55 flame", that is the flame must be widened. For obtaining this result, I mount a pitched spinner 35, in front of the burner, in position to be struck only by the sprayed oil. This spinner is preferably mounted upon a 60 screw or the like 36, extending forwardly from the valve 27. The atomized or sprayed fuel strikes the pitched blades 37 of the spinner 35 and causes rapid rotation of the latter

and hence, particles of oil are thrown off by centrifugal force and the flame is effectively 65 widened.

Excellent results are obtainable from the details disclosed and they therefore constitute the preferred form of my invention, but within the scope of this invention as claimed, 70 numerous minor changes may be made.

I claim:

1. In an oil burner, a burner body having fluid and oil ducts, a tubular upstanding fluid supply neck supporting said burner body and having an oil port detachably connected with said oil duct at the exterior of the neck, a drip pan having an opening in its bottom in which the lower end of said neck is secured, said pan being disposed under the detachable connection between said duct and port to receive all dripping oil when such connection is broken, a coupling secured against the lower side of the pan bottom for attaching a fluid supply pipe in communication with said neck, the upper side of said coupling having a relatively wide and shallow flat bottomed channel-way, and a fluid controlling valve plate slidably in said channel-way and slidably engaging the bottom of 80 said pan.

2. A mechanically atomizing oil burner comprising a high pressure oil pipe having its tip formed with a narrow internal frusto-conical valve seat, a valve adjustable toward 95 and from said seat, said valve being of substantially the same diameter as said tip and having a narrow frusto-conical face to contact with said seat in spraying a hollow cone of oil from the tip, and means for supplying 100 low pressure air to the sprayed cone comprising a sleeve surrounding and widely spaced from said tip and valve, said sleeve terminating in rear of the zone of spray to supply air to the sprayed cone without obstructing the same.

3. The combination with an oil burner having mechanically atomizing means for producing a hollow cone of sprayed fuel, including a central, forwardly and rearwardly 110 adjustable valve; of a spinner carried by said valve and spaced forwardly from all parts of the burner in position to be struck by the fuel sprayed from said atomizing means after the spray leaves the burner, 115 whereby to widen the zone of spray.

4. A structure as specified in claim 1; together with a spray-actuated spinner mounted at the front side of said valve and bodily movable with the latter, said spinner being spaced forwardly from all parts of the 120 burner.

In testimony whereof I have hereunto affixed my signature.

WILLIAM L. BAKER.
